UNITED STATES PATENT OFFICE.

FRANKLIN ANDREW STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 30, 1921. Serial No. 525,986.

To all whom it may concern:

Be it known that I, FRANKLIN ANDREW STEARN, a citizen of the United States, residing at Paterson, in the county of Passaic, State of New Jersey, have invented certain new and useful Improvements in Telephone-Exchange Systems, of which the following is a full, clear, concise, and exact description.

10 This invention relates to telephone exchange systems and more especially to systems of the character wherein automatic switching apparatus is employed for the establishment of conversational connections.

15 In certain types of telephone exchange systems the automatic switching apparatus used for building up connections is arranged to be controlled in its operation by a controlling mechanism or sender, conveniently located at the central office in proximity to the switching apparatus itself. Where the system is one of the character in which the establishment of a connection involves the participation of an operator as well as the 20 automatic selective switches it may be the duty of the operator to receive the designation by one means or another and to produce a record of the same on equipment, such as a keyboard, at her position. The record, once set up on the keyboard, is transferred therefrom to the register controlling mechanism and there recorded on controlling registers which later exercise a control over the selective movements of the automatic 25 switches.

30 The operator's keyboard, together with the individual mechanism and devices immediately associated therewith, are capable of determining the transfer of a large 35 number of different wanted designations to the registers of a controlling sender. Moreover, the single keyboard at a given operator's position is provided in common to a plurality of register senders and is fitted to 40 transfer designatory records to any one of these register senders. The transfer of the record from the keyboard to the several registers of the sender takes place over a control circuit which serves to interconnect 45 the keyboard at the operator's position with the particular one of the register senders that is taken for use at the time. This may be accomplished by means of impulses sent in codes, or in any other desired fashion, 50 over the control circuit and directed to the

several registers of the sender. Since it is convenient to send the impulses over the control circuit in a sequential order, bearing a relation to the order in which the digits or characters constituting the designation occur, it is desirable to associate the 60 said control circuit with the resistors in succession in order that each register may receive its proper record.

65 The register controlling sender, having received the complete registration identifying the number of the called line, next, becomes effective to control the selective switches in accordance with its registration. The directory numbers of subscribers' lines 70 are, of course, based on the decimal system, but, for reasons of economy, it is desirable to construct the switches and senders for operation on a non-decimal principle. Therefore, the record established on the 75 registers of the sender is non-decimal, yet the registration on each of the several registers bears a certain and definite relation to the digits of the called number.

80 It is thus possible to greatly simplify the registers by decreasing the total number of different combinations each register is capable of recording. This is accomplished by providing a single controlling device which coacts with the registers to secure any extent of control over the selective switch that the wanted number may require.

85 The object of the present invention is to improve telephone systems of the foregoing character by the use of a single controlling device which causes the association 90 of the control circuit with the register controlling mechanism and which cooperates with said mechanism to determine the effect of the registration on the selective switches. 95

A feature of the invention relates to the provision of a relay which acts to associate the control circuit with the registers in succession while the record is being received, and which serves to modify the control of 100 the registers over the selective switch to determine the extent of movement the selective switch is permitted to take under the control of the registration on such registers.

105 Such other features and advantages as are contemplated by the present invention will be more clearly understood from the following detailed description and also from the appended claims.

Referring to the drawing, the several figures when taken in the order illustrated in Fig. 7, disclose so much of a telephone exchange system as is necessary to an understanding of the invention.

Fig. 1 shows a trunk line incoming from a distant office and terminating in an incoming automatic selector switch.

Fig. 2 illustrates the circuits of a final selector switch which cooperates with the incoming selector to extend connections to called subscribers' lines in the office where they are located.

Fig. 3 shows an operator's keyboard and the individual equipment associated therewith by means of which the designations of called subscribers' lines are manually recorded.

Fig. 4 shows one of a plurality of trunk selector-sender selector units, the function of which is to automatically select the particular incoming trunk circuit assigned for use by the operator, to automatically select one of a plurality of idle senders, and to associate the selected idle sender and the operator's keyboard with each other and with said trunk circuit.

Figs. 5 and 6 illustrate one of the register senders located at the central office and which serves to control the incoming and final selector switches in accordance with the designations set up by the operator on her keyboard.

Fig. 7 shows the order in which the several figures are arranged.

35 General description of the system and apparatus.

The automatic switching system disclosed in this application is particularly well adapted for the disposition of inter-office calls where the calls are received by a manual operator in an originating office from lines terminating, either directly in such originating office, or lines which have been extended thereto, and which calls are destined for a subscriber's line in a distant office equipped with machine switching apparatus. The calling line having been extended to the A operator in the originating office, she receives the desired number orally, and on learning that it is intended for a subscriber's line in a distant office equipped with selective switches, such as those shown in Figs. 1 and 2, communicates with the operator at such mechanical office by means of an order wire. The operator in the called office assigns an idle trunk for extending the calling line and which trunk terminates in an incoming selector switch, such as shown in Fig. 1. Also the A operator at the same time communicates the number of the called subscriber's line to the operator in the called office.

The selective switches shown in Figs. 1 and 2 are of the power driven type in which the brush shafts are operated in a continu-

ous movement from a constantly operating source of power, and which, during their movement, send out impulses in measurement of the distance traversed. These impulses reverted from the switch are received by register senders located at the central office, and on which registrations have previously been made in accordance with the designation of the called line. The register senders respond to the reverted impulses, and when the proper number has been received, bring about a termination of the movement of the switch by disconnecting the constantly operating source of power. A switch of the general type and construction as those shown in Fig. 1 and Fig. 2 is illustrated and described in detail in the patent to Craft and Reynolds, 1,123,696, issued January 5, 1915.

A plurality of register senders, one of which is illustrated in Figs. 5 and 6, are provided at the office, and any one of these that happens to be idle at the time the call is received from the distant office may be taken for use to record the designation of the called line as soon as the operator sets up the same on the keyboard at her position. Briefly, the register sender comprises a plurality of relay registers each of which consists of a plurality of relays, some of which are marginal and others sensitive. These relays and the circuits they control are shown in Fig. 6. In Fig. 5 there is shown a controlling sequence switch 510 which first operates from position to position to cause the association of the control circuit, which leads from the operator's keyboard, with the successive registers shown in Fig. 6 for the purpose of transferring the registration from the keyboard to these registers. Moreover, there is provided for each sender a set of counting relays shown in the upper part of Fig. 5, and a stepping relay 520 which co-acts therewith to control over a fundamental circuit the selective movement of the switches in accordance with the character of the registration set up on the register relays.

The operator's keyboard, shown in Fig. 3, consists of four rows of numerical keys; the thousands row 300, the hundreds row 301, the tens row 302 and the units row 303. Although the majority of the keys of each row have been omitted to save space in the drawing, it will be understood that each row of keys consists of ten in number. By depressing a single key in each of the four rows on her board, the operator may make a record of the number of any line in the 10,000 line office of the exchange. The keys are of the locking type which mechanically lock in their depressed or actuated position and remain actuated until released by the energization of a common release magnet. There is provided one such magnet for each row of keys.

Individual to the operator's keyboard there is provided a controlling sequence switch 310 and numerous relays, the purpose of which is to transmit impulses in the proper order of sequence over a set of control conductors to the selected idle register sender, which impulses identify the character of the number written upon the keyboard. In other words, the sequence switch 10 310 and its cooperating elements serve to transfer by means of impulses the numerical record set up by the operator on the keyboard over a control circuit to the sender where this record is recorded on the register relays.

The time required by the operator in setting up a number on her keyboard and for the same to be transferred to the controlling register sender is small as compared with the time that the sender may be necessarily associated with the switches in establishing a connection. This means that an operator through the agency of a single keyboard may set up the records of a plurality of calls before the senders taken for use in controlling the establishment of such calls are rendered free for further use. To this end the plurality of senders are available to the operator and may be associated with her keyboard. The association is accomplished by means of trunk selector and sender selecting units, one of which is shown in Fig. 4, there being a plurality of these for each operator's position.

These units each consist of a trunk selector switch 427, which has access to terminals representing all of the trunks 100 and 101 incoming to the operator's position. Moreover, the sender selector switch of the unit, 428, has access to all of the senders. By any suitable arrangement the trunk selector-sender selector units may be allotted for use, and when one is started in operation it operates to find the trunk assigned by the operator and to find an idle register sender and to associate the idle register sender thus selected with the operator's keyboard. The switches 427 and 428 are of the power driven type, similar in most respects to the switch referred to in the above-mentioned patent to Craft and Reynolds.

The several sequence switches disclosed in the drawing, namely sequence switches 110, 210, 310, 410 and 510 may be of the same construction as the one shown in the patent to Reynolds and Baldwin 1,127,808, issued February 9, 1915.

Referring particularly to the register senders shown in Figs. 5 and 6, there are seen to be five different registers for receiving the registration characterizing the number of the called lines. The incoming brush register consists of relays 609, 611 and 612; the incoming group register of relays 613 and 614; the final brush register of relays

608, 610 and 607; the final tens register of relays 605, 606, 603 and 615 and the final units register of relays 600, 601, 602 and 604.

As regards the incoming selector switch 125, shown in Fig. 1, the construction of this switch is such that a maximum of five controlling impulses is sufficient to control it in any selection. That is to say, the switch only has five sets of brushes, and the grouping in the terminal bank is such that a brush section does not consist of more than five different groups. Therefore, in both the brush selecting and group selecting movements of the incoming switch 125, a maximum of five impulses reverted from the switch to the sender is sufficient to control any selection. This means that the incoming brush and group registers need only to be capable of registering five different combinations. The same is true of the final selector switch 215 as regards its brush selecting movement, this switch likewise only being provided with five sets of brushes. Here, however, each brush has access to 100 terminals, these 100 terminals being divided up into ten groups of ten terminals each.

The final tens and units registers are arranged like the other registers of the sender to take only a maximum of five different settings, but as mentioned, the tens and units selections may involve more than five impulses. In order that the registers may control the final switch when the selection involves a digit greater than four, there is provided a translation or controlling relay 500, which operates provided the tens or units digit is greater than four. The effect of this relay is to add five impulses to the value of the registration contained on the corresponding register. As will be brought out hereinafter, the relay 500, which acts as a controlling and translating device for determining the influence of the register upon the extent of operation of the selector switch during the establishment of the connection, also serves to cause the successive association of the control circuit, leading from the keyboard, with the several registers during the transfer of the record.

Detailed description of operations in the establishment of a connection—the operator receives the call.

Assume that a call has originated on a subscriber's line and has been extended to an A operator's position in an originating office, not shown in this drawing. The operator receives the name of the office and the number of the line therein from the subscriber, and by means of an order wire interconnecting her position and the position of the operator in the office shown, requests of the latter operator the assignment of an idle trunk. An inter-office system of this character where A operators extend calling lines

to mechanical offices, there to be handled by cordless B operators is shown and described in the patent to Lundell and Clark No. 1,342,823, issued June 8, 1920.

5 The operator in the office shown informs the originating manual operator that the trunk 100, 101 is assigned for use, and that she may complete the connection over that trunk. At the same time, the operator making the assignment depresses the key 119. A circuit is thereupon closed from ground through the contacts of said key, lower right contact 109 (1), winding of sequence switch magnet 110 to battery. Sequence switch 110 10 moves out of position 1, entering position 2 where it initiates the operation of an allotted sender selector unit in a manner to be taken up presently.

20 *Operation of trunk selector and sender selector.*

When the sequence switch 110 moves into position 2, a circuit is established from ground through the lower contact 108 (1+12 $\frac{1}{4}$), outer back contact of relay 104, lower right contact 111 (2), conductor 144, upper and lower contacts 419 (1), winding of relay 404 to battery. Relay 404 operates and closes a circuit from battery through the right-hand winding of relay 400, upper left contact 414 (1+1 $\frac{1}{2}$), lower right contact 414 (1+3), left contact of relay 404, upper right contact 422 (1+3) to ground. Relay 400 becomes energized and completes a circuit from battery through the winding of sequence switch 410, upper left contact 417 (1), outer right front contact of relay 400 to ground. Sequence switch 410 moves out of position 1 and into position 2. As the sequence switch advances from position 1 into position 2, the original circuit of relay 404 is opened at contact 419, but this relay remains energized in a circuit from battery through its winding and inner right contact, lower right contact 416 (1+4), commutator 459, brush 460 to ground. With sequence switch 410 in position 2, both the sender selector 428 and the trunk selector 427 of the allotted unit are started in operation, one 45 to find an idle sender and the other to find the incoming trunk 100, 101, which the operator has assigned for use in extending the connection.

55 The brush shaft 450 of the sender selector is driven upwardly by means of the constantly operating source of power, which is rendered effective by the updrive power magnet 407. The magnet 407 is energized in a circuit from battery through the winding of said magnet, right contact 417 (2), outer right front contact of relay 400 to ground. As the brushes 441, 442, 443 and 444 of the sender selector encounter the terminals representing each register sender, a 60 test is made to determine the busy or idle

condition of the corresponding sender. If the register sender corresponding to the first set of terminals, upon which the brushes of the switch 428 are standing, is busy, the test brush 443 finds a ground potential thereon. Consequently, when the sequence switch 410 reaches position 2, a circuit is closed from battery through the right hand winding of relay 400, upper right contact 411 (1+5), upper left contact 411 (1+2), left front contact of relay 400, upper right contact 412 (1 $\frac{3}{4}$ +4), lower right contact 412 (1+9), conductor 451, brush 443 to the grounded test terminal, the ground being applied to such terminal in a manner to be explained hereinafter. It will be noted that the circuit just traced for the relay 400 leads through a front contact of said relay and through the upper right contact 412, which is closed in position 1 $\frac{3}{4}$ to 4. This circuit is closed prior to the time the upper left contact 414 opens as the sequence switch 410 passes from position 1 into position 2, whereby if the first sender is busy, the relay 400 remains locked in position 2 of sequence switch 410, and the circuit previously traced for the updrive power magnet 407 is closed to advance the brush shaft 450 off the first set of terminals and on to the next in search of an idle sender. 65

When an idle register sender is found, the test brush 443 failing to find a ground potential on the corresponding test terminal, opens the holding circuit of relay 400 which becomes deenergized. Relay 400 opens the circuit of the updrive power magnet 407, causing the brushes to come to rest on the terminals representing the selected idle sender. Moreover, relay 400 completes a circuit from ground through its outer right back contact, lower left contact 423 (2), winding of sequence switch 410 to battery. Sequence switch 410 advances out of position 2 and into position 3. 70

At the time sequence switch 410 reaches position 2, a circuit is also closed for the updrive power magnet 405 of the trunk selector switch 427, and the brush shaft 449 is moved upwardly to trail the brushes 435, 436, 437, 438, 439 and 440 over the terminals 75 representing the different trunk circuits incoming from the distant office. The circuit for magnet 405 is traceable from battery through the winding of said magnet, lower left contact 414 (2+3), lower right contact 414 (1+3), left contact of relay 404, right contact 422 (1+3) to ground. As the brush shaft 449 moves upwardly over the terminals of the bank, a test is made of each set of terminals to determine which one of the incoming trunk circuits 100, 101 has been 80 taken for use by the operator. When the assigned trunk is reached, a circuit is closed from battery through the winding of relay 401, upper contact 424 (1 $\frac{3}{4}$ +3), brush 437, 85

conductor 141, lower left contact 112 (2) of sequence switch 110, upper right contact 112 (2+3), inner back contact of relay 104, lower left contact 113 (1+10), lower right contact 113 (2+3) to ground. Relay 401 operates in this circuit and closes a temporary locking circuit for itself traceable from battery, through the winding of said relay, lower contact 424 (1 $\frac{3}{4}$ +11), right front contact of relay 401, upper left contact 422, (1+3 $\frac{1}{2}$) to ground. Relay 401 by energizing completes a circuit at its left contact for relay 402 and relay 402 becomes energized. Relay 401 at its right back contact 15 opens the circuit of relay 404, which becomes deenergized and in turn opens the circuit of the power magnet 405 causing the brush shaft 449 to cease its upward movement. Relay 404 in addition to opening the power magnet circuit, completes a circuit from ground through its outer right contact, upper right contact 409 (3), winding of sequence switch 410 to battery, driving said sequence switch out of position 3 and into 20 position 4. As sequence switch 410 leaves position 3 $\frac{1}{2}$, the temporary holding circuit of relay 401 is opened at the left contact 422, but this relay is now held in a locking circuit traceable from battery through its winding, lower contact 424 (1 $\frac{3}{4}$ +11), right front contact of relay 401, innermost left contact of relay 402, brush 440, conductor 139, upper left contact 112 (2+11), upper right contact 112 (2+3), and thence 25 to ground as described at the lower right contact 113.

It was explained that the sequence switch 410 is driven from position 3 and into position 4 as soon as relay 404 deenergizes following the termination of the operation of the trunk selector 427. This is on the assumption that sequence switch 410 has reached position 3 which it does immediately following the termination of the operation of the sender selector switch 428. It should also be noted that the sequence switch 410 may pass from position 2 and into position 3 following the selection of a sender during the time that the trunk selector switch 427 is in operation without disturbing the function of this latter switch. If the trunk selector switch succeeds in locating the assigned trunk prior to the time the sender selector switch 428 finds an idle sender, then sequence switch 410 remains in position 2 until relay 400 becomes deenergized. Thereafter it advances into position 3, and finding the relay 404 deenergized, immediately moves into position 4. Hence the sequence switch 410 finally moves into position 4 after both selector switches have completed their functions regardless of which was the first to finish its operation.

In position 4 of sequence switch 410, a

circuit is immediately closed from battery, through the right hand winding of relay 400, upper right contact 411 (1+5), lower right contact 411 (4+5), lower left contact 420 (4+5), outermost left contact of relay 402, brush 435, conductor 143, lower left contact 120 (2+11), upper left contact 120 (2) to ground. Relay 400 becomes operated and closes a circuit from ground through its outer right front contact, upper left contact 417 (4), winding of sequence switch magnet 410 to battery, advancing said sequence switch out of position 4 and into position 5. Relay 400 remains energized in position 5 of the sequence switch in the circuit above traced.

At the time the relay 400 deenergizes, when the sender selector finds an idle register sender, a circuit is closed as follows temporarily to render the selected sender busy to other switches: ground, through the left back contact of relay 400, upper right contact 412 (1 $\frac{3}{4}$ +4), lower right contact 412 (1+9), conductor 451, brush 443, and thence to the multiples of the terminals representing the selected sender. Later when the sequence switch 410 moves from position 2 and into position 3, as previously explained, the busy ground potential is furnished over the lower left contact 412, closed in position 2 $\frac{3}{4}$ to position 8 $\frac{1}{4}$, lower right contact 412 (1+9), and thence to the multiple terminals in the bank of the sender selector switch 428. Immediately after the sequence switch 410 reaches position 4, a circuit is closed from ground through the right front contact of relay 402, lower right contact 421 (4+6), upper right contact 421 (4+5), brush 441, conductor 445, upper left contact 518 (1) of sequence switch 510, right hand winding of relay 501 to battery. Relay 501 operates in this circuit and completes a circuit from ground through its left front contact, upper left contact 507 (1), winding of sequence switch magnet 510 to battery. The sender sequence switch 510 moves into position 2, thus preparing the circuits of the sender for receiving the incoming registration from the operator's keyboard. The relay 501 upon energizing closes a circuit from battery through its right hand winding and right contact, conductor 447, brush 448, and thence to ground at the contact 412 as previously traced. Relay 501 also closes a circuit from battery through its right hand winding, thence through its left hand winding, upper left contact 508 (2+18) to ground. This latter circuit, however, is not sufficient to maintain the relay 501 energized when ground is removed from the conductor 447. In other words, the relay 501 remains energized only so long as ground is held on the conductor 447 until sequence switch 410 leaves position 8 $\frac{1}{4}$. The purpose of the circuit through the left hand winding of relay 120

501 is to provide a ground potential on the conductor 447 and thence on the multiple terminals in the bank of the sender selector to render the sender non-selectable provided 5 the sender selector 428 restores to its normal position prior to the time that sequence switch 510 advances through position 18.

10 *The operator records the call number on her keyboard.*

15 At the time the originating manual operator requests the assignment of an idle trunk, she also orally communicates to the operator in the mechanical office the number of the called subscriber's line. This 20 number is thereupon set up on the operator's keyboard. Assume, for example, that the number of the wanted line is 6321, the last two digits of which it will be noted are less than four, signifying as will be seen herein-after, that no translation is required with respect to the tens and units selecting movements of the final selector switch 215. Accordingly, the operator depresses the No. 6 25 thousands key 304, the No. 3 hundreds key 305, the No. 2 tens key 307, and the No. 1 units key 309. These keys lock in their depressed positions as fast as they are actuated, and upon the depression of a key in 30 each row, the common row contacts 315, 316, 317 and 318 are opened. Upon the depression of the first key 304, a circuit is closed from battery through the resistance 344, winding of relay 345, contact 348 (18 $\frac{3}{4}$ +6) 35 of sequence switch 310, right contacts of key 304, conductor 358 to ground. Relay 345 does not energize since its winding is shunted by a circuit from battery through the resistance 344, left contact of relay 345, conductor 359, through contacts 316, 317 and 318 in parallel, right contacts of key 304, conductor 358 to ground. The contact 315 opened when key 304 was depressed, but since none of the remaining keys in the other 40 three rows are actuated, contacts 316, 317 and 318 are still closed. Upon the depression of the key 305 in the hundreds row, contact 316 is opened, but contacts 317 and 318 are still closed to maintain the shunt 45 around the winding 345. However, when the last key 309 is depressed and the last row contact 318 is opened, all possible paths for maintaining the shunt around the winding 345 are opened and the said relay becomes energized. The energizing circuit of 50 relay 345 may be found by inspection to lead through the right hand contacts of each of the depressed keys so that said relay would remain operated as long as any key 55 in any row is in its actuated condition.

60 As soon as the last key is depressed and the relay 345 is operated, a circuit is closed from ground through the right front contact of said relay, upper right contact 343 (1), outer right back contact of relay 320, con-

ductor 360, upper left contact 326 (1), lower right contact 326 (1), conductor 354, lower left and upper left contacts 413 (5), middle left contact of relay 402, brush 438, conductor 140, lower left contact 116 (2), winding of sequence switch magnet 110 to battery. The sequence switch 110 thereupon advances out of position 2 and into position 3. As sequence switch 110 reaches position 2 $\frac{3}{4}$, the holding circuit of relay 401 70 previously traced is shifted so that it now leads to ground through the lower right contact 112 (2 $\frac{3}{4}$ +18). Moreover, as sequence switch 110 leaves position 2, it opens at the upper left contact 120 the holding 75 circuit hereinbefore traced for relay 400. Relay 400 thereupon releases its armatures and a circuit is closed from ground through the outer right contact of said relay, lower left contact 423 (5), winding of sequence 80 switch magnet 410 to battery. Sequence switch 410 leaves position 5 and moves into 85 position 6.

With sequence switch 410 in position 6, a circuit is closed from ground to the right 90 front contact of relay 402, winding of relay 403, lower contact 415 (6), conductor 353, upper right contact 319 (1+5), upper left contact 319 (1), left hand winding of relay 320 to battery. Relay 320 operates and 95 locks in a circuit through its left hand winding and left contact. Relay 403 also operates in series with relay 320 and closes a circuit from battery through the right hand winding of relay 400, upper left and 100 upper right contacts 414 (6+7), left contact of relay 403 to ground. Relay 400 becomes energized and closes a circuit from ground through its outer right contact, upper left contact 417 (6), winding of sequence 105 switch 410. Sequence switch 410 moves into position 7 and relay 400 remains energized. In position 7 the lower left contact 415 is opened, but the energizing circuit of relays 320 and 403 110 is maintained over the upper left contact 415 and the inner right contact of relay 400. The relays 400 and 403 by energizing at this time extend the three impulse control conductors 357, 356 and 355 through the brushes of the sender selector switch 428 to the selected register sender. Thus the operator's keyboard is effectively associated through the medium of the sender selector with the sender shown in Figs. 5 and 6. 115

120 *Registration of called number on the register sender.*

When relay 320 operates a circuit is closed from ground through the right front contact of relay 345, upper right contact 343 (1), outer right front contact of relay 320, lower left contact 342 (1), winding of sequence switch 310 to battery. Sequence switch 310 leaves position 1 and moves into 125 130

position 2. With sequence switch 310 in position 2 and the sender sequence switch 510 also in position 2, the impulse control circuit interconnecting the operator's keyboard and the register sender, is rendered effective for transmitting a code of impulses characterizing the thousands digit to cause a corresponding registration on the registers of the sender. In position 2 of the sequence switch 310, a circuit is first closed from battery, resistance 340, upper contact 341 (2), winding of relay 339 to ground. Relay 339, however, remains inert inasmuch as its winding is shunted by a path leading through the outer back contact of said relay and the normal contact at the left hand armature of relay 338 to ground. Another circuit is closed from battery through the low resistance 350, upper left contact 351 (1+6), left contacts of thousands key 304, conductor 361, lower left contact 327 (1 $\frac{3}{4}$ +2), lower left contact 326 (1 $\frac{3}{4}$ +5), conductor 356, inner right contact of relay 403, brush 441, conductor 445, lower right contact 518 (1 $\frac{3}{4}$ +2), conductor 529, right hand windings of relays 609 and 612 to ground. Relay 609 is marginal, but since only the low resistance 350 is included in the circuit, this relay becomes energized. Relay 612 also becomes energized. The relays 609 and 612 lock in circuits from battery through their left hand windings and left contacts, thence over conductor 536, upper right contact 513 (1 $\frac{3}{4}$ +14) to ground. Another circuit is closed from ground through the inner contact of relay 339, left hand low resistance winding of relay 338, upper left contact 337 (2), middle contacts of key 304, conductor 362, lower right contact 329 (2), conductor 357, outer right contact of relay 403, brush 442, conductor 446, lower right contact 516 (1+5), upper right contact 516 (1 $\frac{3}{4}$ +2), conductor 534, left hand winding of relay 611 to battery. Relay 611 is marginal, but since only the low resistance winding of relay 338 is included in series therewith, is becomes energized and locks in a circuit through its right hand winding and inner right contact over conductor 536, upper right contact 513 (1 $\frac{3}{4}$ +14) to ground. Relay 338 also operates, and at its left hand armature removes the shunt from around the winding of relay 339. Relay 339 thereupon becomes energized. The circuit through the left hand winding of relay 338 and the left hand winding of relay 611 is now closed to ground through the left hand armature and front contact of relay 338. When relay 338 operates, it closes a circuit from battery, through the upper right contact 363 (2), low resistance 335, right contact of relay 338, high resistance 331, lower left contact 330 (2+5), conductor 355, lower left and upper left contacts 411 (6+7), left front contact of relay 400, lower right and upper right contacts 413 (6+7), brush 444, conductor 448, left hand winding of relay 613, conductor 543, lower left contact 515 (2), winding of relay 502 to battery. Due to the inclusion of the high resistance 331 in the circuit traced, marginal relay 613 does not receive sufficient current to energize. Relay 502, however, operates and closes a circuit from battery through the winding of sequence switch magnet 510, front contact of relay 502, lower right and upper right contacts 505 (2), right back contact of relay 500, lower contact 503 (1+5) to ground. Sequence switch 510 moves out of position 2 and into position 3. When sequence switch 510 leaves position 2, it opens at its upper right contact 516 the holding circuit of relay 338 and at its lower left contact 515 opens the circuit of relay 502. Relay 338 upon deenergizing completes a circuit from ground through the normal contacts at its left hand armature, outer armature and front contact of relay 339, upper right contact 321 (2), winding of sequence switch magnet 310 to battery, driving said sequence switch out of position 2 and into position 3. Sequence switch 310 on leaving position 2 opens the circuit of relay 339 permitting the same to deenergize. In the manner above described, the incoming brush register has been positioned in accordance with the designation set up on the operator's keyboard by means of code impulses transmitted from the keyboard over the impulse control circuit to the sender. The next operation that will take place is the transmission in a similar manner of impulses for setting the incoming group register.

With sequence switch 310 in position 3 a circuit is closed from battery through the low resistance 340, lower right contact 341 (3), winding of relay 322 to ground. Relay 322 does not operate because it is shunted by a path leading through its inner back contact and the normal contacts at the left hand armature of relay 323 to ground. Another circuit is closed from battery through the low resistance 350, upper left contact 351 (1+6), left hand contacts of key 305, upper left contact 329 (2 $\frac{3}{4}$ +3), conductor 357, outer right contact of relay 403, brush 442, conductor 446, lower right contact 516 (1+5), upper left contact 517 (2 $\frac{3}{4}$ +3), conductor 531, right hand windings of relays 608 and 607 to ground. Since only the low resistance 350 is included in this circuit, marginal relay 608 becomes operated and also the sensitive relay 607. These two relays lock in circuits through their left hand windings and left contacts over conductor 536 to ground at the upper right contact 513 (1 $\frac{3}{4}$ +14). Another circuit is also closed

from ground through the outer right contact of relay 322, right hand low resistance winding of relay 323, upper left contact 333 (3), middle contacts of key 305, conductor 362, upper right contact 327 (3), lower left contact 326 (1 $\frac{3}{4}$ +5), conductor 356, inner right contact of relay 403, brush 441, conductor 445, lower left contact 518 (2 $\frac{3}{4}$ +3), conductor 530, left hand winding of relay 610 to battery. Since only the low resistance winding of relay 323 is included in series with marginal relay 610, this latter relay becomes energized. Relay 610 locks in a circuit through its right hand winding and inner right contact to the grounded conductor 536. Relay 323 also operates and closes a locking circuit for itself and the register relay 610 through the left hand front contact of said relay 323 to ground. 10 Relay 323 also opens the shunt around relay 322 and this latter relay becomes energized in the circuit previously traced. With relay 323 operated, another circuit is completed from ground through the contact 324 (3), low resistance 325, right contact of relay 323, high resistance 331, lower contact 330 (2+5), conductor 355, and thence as previously traced to the conductor 448, right hand winding of relay 614, conductor 537, right contact 514 (3), right hand winding of relay 500 to battery. Due to the high resistance 331, relay 614 cannot operate. Relay 500, however, attracts its armatures and a circuit is closed from ground through the lower left contact 503 (1+5), right front contact of relay 500, upper left and lower left contacts 505 (3), back contact of relay 502, winding of sequence switch 510 to battery. Sequence switch 510 moves out of position 3 and into position 4, and in so doing opens the previously traced circuit for relays 323 and 500. Relay 323 upon deenergizing closes a circuit from ground through its left normal contacts, inner front contact of relay 322, lower right contact 321 (3), winding of sequence switch magnet 310 to battery. Sequence switch 310 moves from position 3 into position 4, and opens the circuit of relay 322.

With sequence switch 310 in position 4, the previously traced circuit for relay 339 is closed, but this relay does not energize so long as its winding is shunted by the normal contacts of relay 338. With sequence switches 310 and 510 in positions 4, a circuit is closed from ground through the inner contact of relay 339, left hand winding of relay 338, upper right contact 337 (4), middle contacts of key 307, conductor 364, upper left contact 328 (4), conductor 357, and thence as previously traced to the conductor 446, lower right contact 516 (1+5), upper left contact 516 (3 $\frac{3}{4}$ +4), conductor 533, left hand winding of relay 606 to battery. Although relay 606 is marginal, it operates

since only the low resistance winding of relay 338 is included in the circuit therewith. Relay 606 locks in a circuit through its right hand winding and inner right contact, conductor 535, upper left contact 513 (1 $\frac{3}{4}$ +14) to ground. Relay 338 also operates and locks through its left front contact as previously described. Relay 338 also removes the shunt from around the winding of relay 339 and this latter relay attracts its armatures. A further circuit is completed from battery through the upper left contact 363 (4), low resistance 335, right contact of relay 338, high resistance 331, lower left contact 330 (2+5), conductor 355, and thence as traced to the conductor 448, right hand winding of relay 615, conductor 542, lower right contact 515 (4), winding of relay 502 to battery. Due to the high resistance 331, the marginal relay 615 does not operate. Relay 502, however, becomes energized and closes the above traced circuit for driving sequence switch 510 into position 5. Sequence switch 510 on leaving position 4, opens the circuits of relays 502 and 338. Relay 338 upon deenergizing closes a circuit as previously traced over the upper right contact 321 for driving sequence switch 310 into position 5.

With sequence switch 310 in position 5, the circuit hereinbefore described is completed for relay 322, but this relay is also shunted at the normal contacts of relay 323. Furthermore, a circuit is closed from ground through the outer contact of relay 322, left hand winding of relay 323, upper right contact 333 (5), middle contacts of key 308, conductor 364, upper right contact 326 (5), lower left contact 326 (1 $\frac{3}{4}$ +5), conductor 356, and thence as previously traced to conductor 445, lower right contact 519 (4 $\frac{3}{4}$ +5), conductor 527, left hand winding of relay 601 to battery. Only the low resistance winding of relay 323 is included in the circuit traced, and consequently the marginal relay 601 becomes operated. Relay 601 locks in a circuit through its right hand winding to the grounded conductor 535. Relay 323 also operates, locks from ground through its left front contact and removes the shunt from around relay 322, whereby this latter relay becomes energized. A further circuit is closed from battery through the low resistance 350, right hand contact 351 (1+6), high resistance 352, left hand contact of key 309, upper right contact 329 (4 $\frac{3}{4}$ +5), conductor 357, and thence as previously traced to conductor 446, lower right contact 516 (1+5), upper right contact 517 (4 $\frac{3}{4}$ +5), conductor 532, right hand windings of relays 600 and 602 to ground. Since the high resistance 352 is included in the circuit traced, relay 600 fails to energize. The sensitive relay 602 attracts its armatures and locks in a circuit through its left hand

winding to the grounded conductor 535. With relay 323 operated, a circuit is completed from ground through the lower left contact 324 (5), low resistance 325, right 5 contact of relay 323, high resistance 331, lower left contact 330 (2+5), conductor 355, and thence to the conductor 448, right hand winding of relay 604, conductor 538, lower left contact 514 (5), right hand winding of 10 relay 500 to battery. Relay 500 operates, but due to the high resistance 331, the marginal relay 604 does not receive sufficient current to become energized. Relay 500 upon attracting its armatures closes 15 the circuit previously traced for advancing the sequence switch 510 out of position 5 and into position 6. Sequence switch 510 on leaving position 5 opens the circuits of relays 500 and 323. Relay 323 on deenergizing closes the circuit already described for advancing sequence switch 310 out of position 5 and into position 6. The complete record has now been transferred from the operator's keyboard and set up on the 20 register relays of the controlling sender. The operator's keyboard is required no longer in connection with the present call and may be released in order that it may be taken for use in connection with subsequent 25 calls.

Release of the operator's keyboard.

When the sequence switch 310 reaches position 6, a circuit is established from battery 35 through the contacts 346, conductor 365, through the key release magnets 311, 312, 313 and 314 in parallel to ground. These magnets become energized and permit the depressed keys in their respective rows to 40 be restored to normal. When the last key has been released, all parallel branches for maintaining the energization of relay 345 are opened, and this relay becomes deenergized. Relay 345 completes a circuit from ground through its right back contact, upper left contact 342 (6), winding of sequence 45 switch magnet 310 to battery. Sequence switch 310 leaves position 6 and moves into position 8. In positions 8 and 9 a circuit is 50 closed from battery through the winding of sequence switch magnet 310, lower left contact 321 to ground whereby said sequence switch continues to move into position 10, which is its second normal position corresponding to position 1. All parts of the 55 operator's keyboard and its individual equipment are now fully restored and in readiness to control the transfer of another record to a register sender when associated therewith.

60 At the time sequence switch 310 leaves position 5, it opens at the upper right contact 319, the circuit which up to this time has been maintaining the energization of relays 320 and 403. These relays become

deenergized, relay 403 opening the circuit 65 of relay 400. Relay 400 releases and completes a circuit from ground through its outer right back contact, lower left contact 423 (7), winding of sequence switch magnet 410 to battery. Sequence switch 410 is driven 70 into position 8 where it prepares the fundamental circuit leading from the sender through the brushes of the trunk finder switch 427 to the incoming selector switch 125. 75

Operation of the incoming selector switch.

The fundamental circuit for controlling the brush selecting operation of the incoming selector switch is now established and 80 may be traced from battery through the right hand winding of relay 104, lower contact 107 (1+4), upper right contact 105 (3+7), conductor 143, brush 435, outermost left contact of relay 402, lower right contact 420 (8), brush 441, conductor 445, upper left contact 519 (6), winding of stepping relay 520, back contact of the 0' counting relay 521 to ground. Relay 104 attracts its armatures and a circuit is closed 85 from ground through the lower contact 108 (1+12 $\frac{1}{4}$), outer front contact of relay 104, lower left contact 109 (2+3), winding of sequence switch 110 to battery. Sequence switch 110 moves into position 5 and relay 90 104 is maintained energized in a locking circuit from battery through its right hand winding, upper left contact 113 (4+7), lower left contact 113 (1+10), inner front contact of relay 104, lower contact 105 (4+9), upper right contact 105 (3+7), conductor 143, and thence to ground as traced 95 over the fundamental circuit. With sequence switch 110 in position 5, the updrive power magnet 122 is energized to cause the 100 upward movement of the brush shaft 145. The circuit of this magnet may be traced from battery through the winding thereof, contact 114 (5), outer front contact of relay 104 to ground at the lower contact 108 (1+12 $\frac{1}{4}$). 105

The stepping relay 520 which also energizes in the fundamental circuit completes 110 a circuit from ground through the lower right contact 513 (6), conductor 545, armature and contact of the stepping relay 520, conductor 546, lower left contact 511 (6), upper right contact 512 (6), conductor 547, right front contact of relay 612, left front contact of relay 611, outer right front contact of relay 609, conductor 616, thence to conductor 555, Fig. 5, back contact of counting relay 548, winding of relay 568 to battery. Relay 568 becomes operated and closes a circuit through its winding and 115 the winding of relay 548 in series, contact of relay 568, upper contact 506 (6) to ground. The relay 548, however, is shunted 120

125

by the circuit previously traced through the contact of said relay 520, and therefore does not energize at this time.

It will be noted that the conductors, such as conductor 616, leading from the contacts of the several register relays in Fig. 6, terminate in small circles which contain the ordinals from 0 to 4. These conductors in practice are connected to the correspondingly designated conductors at the armatures of the counting relays shown in Fig. 5, but have been omitted from this disclosure in order to avoid unnecessary complications.

As the brush shaft 145 of the incoming selector switch moves upwardly under the influence of the power magnet 122, the commutator brush 133 encounters the first metallic circuit of commutator 136, and a circuit is completed from battery through the right hand winding of relay 104, upper left contact 113 (4+7), lower left contact 113 (1+10), inner front contact of relay 104, lower right contact 105 (4+9), upper right contact 107 (4 $\frac{3}{4}$ +5), commutator 136, brush 133 to ground. This circuit maintains the energization of relay 104 and shunts the stepping relay 520 at the sender. Relay 520 becomes deenergized and opens the shunt circuit around the winding of the counting relay 548, permitting this relay to operate and lock in series with the relay 549. When, an instant later, the brush 133 engages an insulated segment of the commutator, the shunt is removed from the winding of relay 520 and this relay becomes energized to complete the stepping circuit now by way of conductor 616 through the front contact of relay 548, back contact of the No. 2' counting relay 549, winding of relay 550, to battery. Relay 550 operates and closes a circuit for itself and relay 549 as above traced, but relay 549 being shunted does not energize at this time. For each brush tripping position passed over by the selector switch, the stepping relay 520 is shunted in the manner described, and an additional pair of counting relays are energized and locked. Finally, when the 0' counting relay 521 becomes operated, it opens the fundamental circuit and also completes a circuit from ground through its front contact, conductor 551, lower contact 507 (6), winding of sequence switch magnet 510 to battery. The sender sequence switch 510 leaves position 6 and moves into position 8. On passing from position 6 to position 8, the contact 506 is opened, permitting all energized counting relays to become released.

As soon, following the opening of the fundamental circuit at the 0' counting relay 521, as the brush 133 engages the next insulating segment of commutator 136, the holding circuit of relay 104 is opened and

this relay becomes deenergized, opening thereby the circuit of the power magnet 122, whereupon the brush shaft 145 comes to rest in position for tripping the desired set of brushes. Moreover, relay 104 completes a circuit from ground through the lower contact 108 (1+12 $\frac{1}{4}$), outer back contact of relay 104, upper left contact 109 (5), winding of sequence switch magnet 110 to battery, driving said sequence switch out of position 5 and into position 6. In position 6 a circuit is closed from battery through the winding of the tripping magnet 124, left contact 115 (6+8) to ground. Magnet 124 operates to rotate the tripping spindle preparatory to tripping the selected set of brushes on the subsequent upward movement of the brush shaft 145.

The fundamental circuit is again closed for controlling the group selecting movement of the incoming switch, and is traceable over the same path as previously described. Relay 104 becomes energized and closes a circuit from ground through the lower contact 108 (1+12 $\frac{1}{4}$), outer front contact of relay 104, lower left contact 109 (6), winding of sequence switch magnet 110 to battery, driving the sequence switch into position 7. In position 7, the relay 104 remains locked in the fundamental circuit over contact 113 as previously explained. The updrive power magnet is energized in a circuit from battery through the winding of said magnet, contact 114 (7), outer front contact of relay 104 to ground at the lower contact 108. The upward movement of the brush shaft 145 is resumed, tripping the selected set of brushes and trailing the same over the terminals of the bank.

The stepping relay 520, which also energizes in the fundamental circuit in series with relay 104, completes a circuit from ground, lower left contact 513 (8+12), conductor 546, contact of the stepping relay 520, conductor 545, upper left and lower left contacts 512 (8), conductor 552, left back contact 613, outer right back contact of relay 614, conductor 617, thence to conductor 554, Fig. 5, upper and lower contacts 504 (6+18), right back contact of relay 500, upper contact 503 (6+18), winding of the 0' counting relay 522 to battery. Relay 522 operates and completes a locking circuit for itself through the winding of relay 521, contact of relay 522 to ground at the upper contact of relay 506 (8). Relay 521, however, does not energize so long as its winding is shunted by the circuit through the contact of the stepping relay 520.

As the brush shaft 145 advances the brushes 126, 127 and 128 into operative relation with the first group of terminals to which these brushes have access, the group selecting commutator brush 134 encounters

the first metallic segment of the commutator 137. This results in the closure of a circuit from battery through the right hand winding of relay 104, upper left contact 113 (4+7), lower left contact 113 (1+10), inner front contact of relay 104, lower contact 105 (4+9), upper left contact 107 (6 $\frac{3}{4}$ +7), commutator 137, brush 134 to ground. Relay 104 is maintained energized, but the stepping relay 520 is shunted and releases its armature to remove the shunt from the winding of the 0' counting relay 521. Relay 521 therefore operates and opens the fundamental circuit and also closes the circuit above traced at its front contact for advancing the sender sequence switch out of position 8 and into position 10. On passing from position 8 to position 10, the sequence switch 510 opens contact 506 and releases 521 and 522 release.

As soon, following the opening of the fundamental circuit at the sender, as brush 134 engages the insulating segment of commutator 137, the holding circuit of relay 104 is opened and this relay becomes deenergized, thereby opening the circuit of the power magnet 122, permitting the brush shaft 145 to cease its upward movement. Relay 104 also completes a circuit over the lower contact 108 and its outer back contact and upper left contact 109 (7) for driving sequence switch 110 out of position 7 and into position 8.

In position 8 of sequence switch 110, a circuit is immediately closed from battery through the left hand winding of relay 104, right contact 106 (2+9), left hand contact 106 (8+8 $\frac{1}{4}$) to ground. Relay 104 operates and locks in the following circuit, providing the first trunk in the group, upon the terminals of which the brushes 126, 127 and 128 are now standing, is busy: battery, through the right hand winding of said relay, lower contact 107 (8+17), lower contact 105 (4+9), inner front contact of relay 104, lower left contact 113 (1+10), upper right contact 113 (8+15 $\frac{1}{4}$), brush 128, to ground on the busy test terminal. Relay 104 by remaining energized completes a circuit from ground through the lower contact 108 (1+12 $\frac{1}{4}$), outer front contact of relay 104, lower left contact 109 (8), winding of sequence switch magnet 110 to battery. Sequence switch 110 moves into position 9 and relay 104 remains energized in its latter circuit, although the original operating circuit through its left hand winding is opened. With sequence switch 110 in position 9 and relay 104 operated, a circuit is closed for the updrive magnet 122 to cause the continued operation of the switch in its trunk hunting movement. The circuit for magnet 122 leads as previously traced over the contact 114, now closed in position 9, and through the front contact

of relay 104. When the brushes 126, 127 and 128 encounter the terminals 129, 130 and 131 of the first idle trunk in the group, no ground potential being found on the test terminal, the circuit of relay 104 is opened 70 and this relay deenergizes to open the circuit of the power magnet 122. Relay 104 also completes a circuit from ground through the lower contact 108 (1+12 $\frac{1}{4}$), outer back contact of relay 104, upper left contact 109 (9), winding of sequence switch magnet 110 to battery. Sequence switch 110 moves out of position 9 and into position 11 where the fundamental circuit is extended through to the final selector switch ready for controlling the brush selection operation thereof.

Operation of the final selector switch.

The fundamental circuit may be traced 85 from battery through the winding of relay 201, contact 207 (1), upper left contact 211 (15+6), conductor 229, terminal 129, brush 126 lower right contact 120 (11+15), lower left contact 120 (2+11), conductor 143, 90 brush 435, outermost left contact of relay 402, right contact 420 (8), brush 441, conductor 445, upper left contact 519 (10), winding of stepping relay 520, back contact of relay 521 to ground. Relay 201 becomes 95 energized and closes a circuit from ground through its left front contact, contact 203 (1), winding of relay 200 to battery. Relay 200 operates and locks in a circuit from battery through its winding and left contact, 100 test terminal 131, test brush 128, upper right contact 113 (8+15 $\frac{1}{4}$), lower right contact 113 (10+17) to ground. It will also be noted that the ground connection from the contact 113 maintains the multiples of test 105 terminal 131 busy to all other incoming selector switches. Relay 200 completes a circuit from ground through its right front contact, upper left contact 204 (1), winding of sequence switch magnet 210 to battery, driving said sequence switch out of position 1 and into position 2. In position 2 relay 201 remains locked in a circuit from battery through its winding and right contact, lower right contact 209 (1+6), upper 110 left contact 211 (15+6), and thence over the fundamental circuit as traced to ground. With relay 201 energized and sequence switch 210 in position 2, a circuit is closed for the power magnet 213 to cause the upward movement of the brush shaft 231 for selecting the proper set of brushes. The circuit of magnet 213 may be traced from battery through the winding thereof, contact 205 (2), left front contact of relay 201 115 to ground.

The stepping relay 520, also operating in the fundamental circuit, closes a circuit from ground through the lower right contact 513 (10), conductor 545, contact of step- 120 125 130

ping relay 520, conductor 546, lower contacts 511 (10), conductor 553, right front contact of register relay 607, left front contact of relay 610, outer right front contact 5 of relay 608, conductor 618, and thence to conductor 555, Fig. 5, back contact of relay 548 winding of relay 568 to battery. Relay 568 operates and completes a locking circuit for itself in relay 548, but the latter relay does not energize due to the shunt around its winding at the contact of the stepping relay 520.

For each brush tripping position passed over by the final selector switch, a circuit is closed from battery through the winding and right contact of relay 201, lower right contact 209 (1+6), upper right contact 211 (1 $\frac{3}{4}$ +2), commutator 226, brush 223 to ground. The closure of this circuit maintains the energization of relay 201 and also shunts the stepping relay 520 in the fundamental circuit. As previously explained, the shunting action of the stepping relay 520 causes the successive energization of the counting relays, and when finally the proper set of brushes have been reached, the 0' counting relay 521 is operated and the fundamental circuit is severed at the sender. Relay 521 in addition completes a circuit through its front contact, conductor 551, lower right contact 507 (10), winding of sequence switch 510 to battery, driving the sequence switch out of position 10 and into position 12.

When, following the opening of the fundamental circuit at the sender, the brush 223 engages the next insulated segment of the commutator 226, the circuit of relay 201 is opened and this relay releases, opening the circuit of the power magnet 213, causing the brush shaft to come to rest temporarily. Relay 201 also closes a circuit through its left back contact and the upper right contact 204 (2) for driving sequence switch 210 out of position 2 and into position 3. In position 3 a circuit may be closed as explained in connection with the incoming switch for tripping the selected set of brushes.

The fundamental circuit is now closed again for controlling the group or tens selective movement of the final switch. This circuit leads as previously traced, and causes the energization of relay 201 and the stepping relay 520. Relay 201 upon the attraction of its armatures closes a circuit from ground through its left front contact, lower right contact 204 (3), winding of sequence switch magnet 210 to battery, whereupon said sequence switch moves out of position 3 and into position 4. In position 4 relay 201 remains locked through its winding and front contact over a circuit similar to the one hereinbefore described. With relay 201 operated, and the sequence switch 210 in

position 4, the updrive power magnet 213 is energized and the brush shaft 231 moves upwardly tripping the selected set of brushes and trailing the selected set of brushes 216, 217 and 218 over the terminals of the bank 70 to select the proper group of ten sets of terminals.

The stepping relay 520 at the sender, also operating in series with relay 201 in the fundamental circuit, completes a circuit from ground through the lower left contact 513 (8+12), conductor 546, contact of relay 520, conductor 545, upper left contact 512 (12), upper left contact 511 (12), conductor 556, right back contact of register relay 603, outer right front contact of relay 606, conductor 619, thence to conductor 557, Fig. 5, back contact of relay 549, winding of relay 550, to battery. Relay 550 operates and prepares a holding circuit for itself in series with the winding of relay 549 to ground at the upper left contact 506 (12). Relay 549, however, being shunted by the stepping relay 520 does not yet operate.

As the brush shaft 231 moves upwardly, driving the brushes 216, 217 and 218 over each succeeding set of ten line terminals, the brush 224 makes engagement momentarily with a metallic segment of the group selecting commutator 227. At each closure of the brush 224 a circuit is completed from battery through the winding and right contact of relay 201, lower contact 209 (1+6), upper right contact 209 (3 $\frac{3}{4}$ +4), commutator 227, brush 224 to ground. This circuit holds the relay 201 energized and shunts the stepping relay 520. When the brushes have reached the proper group of ten terminals, the 0' counting relay 521 finally operating opens the fundamental circuit at its left back contact, and at its left front contact closes the circuit traced for driving the sender sequence switch out of position 12 and into position 14.

As soon, after the fundamental circuit is 110 opened, as brush 224 disengages the conducting segment of commutator 227, relay 201 becomes deenergized and opens the circuit of the power magnet 213. Relay 201 furthermore completes a circuit over its left back 115 contact and the upper right contact 204 (4) for driving sequence switch 210 out of position 4 and into position 5.

Lastly, the fundamental circuit is closed 120 in the manner hereinbefore traced for controlling the units selective movement of the switch to direct the brushes 216, 217 and 218 on to the terminals of the called subscriber's line. Relays 201 and 520 operate in the fundamental circuit and the former 125 of the relays closes a circuit similar to the one hereinbefore described for driving sequence switch 210 out of position 5 and into position 6. With sequence switch 210 in position 6 and relay 201 energized, the 130

power magnet 213 again has its circuit closed over contact 205 and the left front contact of relay 201.

Stepping relay 520 on energizing in series with relay 201 closes a circuit from ground through the lower right contact 513 (14), conductor 545, contact of relay 520, conductor 546, lower left and upper right contacts 511 (14), conductor 558, right front contact 10 of register relay 602, left front contact of relay 601, outer right back contact of relay 600, conductor 620, thence to conductor 526, Fig. 5, back contact of relay 523, winding of relay 524 to battery. Relay 524 operates and 15 prepares a locking circuit for itself in series with the winding of relay 523, but the relay 523 cannot operate until the shunt is removed at the contact of the stepping relay 520.

20 The brush shaft 231 moves upwardly and for each set of terminals traversed by the brushes 216, 217 and 218, the commutator brush 222 makes engagement with a metallic segment of the commutator 228. This engagement results in the closure of the circuit from battery through the winding and right contact of relay 201, lower contact 209 (1+6), contact 212 (5 $\frac{3}{4}$ +6), commutator 228, brush 222 to ground. Relay 201 25 mains operated, but the stepping relay 520 is shunted. When the selected set of terminals 219, 220 and 221 in the selected group of tens have been reached by the brushes, the 0' counting relay 521 operates and opens 30 the fundamental circuit. Shortly thereafter brush 222 disengages the corresponding metallic segment of commutator 228. Therefore, the holding circuit of relay 201 opens, and this relay becomes deenergized 35 40 to open the circuit of the power magnet 213 causing the switch shaft to cease its upward movement. Relay 201 deenergizing also closes a circuit at its left back contact and the upper right contact 204 (6) for driving 45 sequence switch 210 out of position 6. Relay 521 on operating also closes a circuit through its front contact, conductor 551, lower right contact 507 (14), winding of sequence switch magnet 510, driving said 50 switch out of position 14 and into position 16.

Release of the register sender.

The units selection having been completed 55 the register sender may now be released since it is no longer required for the present connection. The sender sequence switch 510, on reaching position 15 on its way to position 16, completes a circuit from ground 60 through the upper right contact 508 (15+18), conductor 446, brush 442, upper right contact 423 (8), winding of sequence switch magnet 410 to battery. Sequence switch 410 leaves position 8 and moves into 65 position 9. In position 9 of sequence switch

410, a circuit is closed from battery through the winding of said sequence switch, lower left contact 423, outer right back contact of relay 400 to ground, whereby the sequence switch 410 is moved out of position 9 and 70 into position 10. In this position the sequence switch 110 of the incoming selector switch 125 is advanced out of position 11. The circuit for causing this advance may be traced from battery through the winding of sequence switch magnet 110, lower left contact 116 (11), conductor 140, brush 438, middle left contact of relay 402, upper contact 426 (10), lower contact 426 (6 $\frac{3}{4}$ +10) 75 to ground. Sequence switch 110 on leaving position 11 opens at its upper left contact 112 the holding circuit of relay 401. Relay 401 becomes deenergized and opens the holding circuit of relay 402. With relay 402 released, a circuit is closed from battery through the winding of sequence switch magnet 410, upper left contact 423 (4+10), right back contact of relay 402 to ground. Sequence switch 410 moves into position 11 80 where the brush shafts of the switches 427 90 and 428 are restored to their normal positions.

The sender selector 428 is released by means of the downdrive power magnet 408, the circuit of which is closed from battery through the winding of said magnet, right contact 418 (11) to ground. The trunk selector switch 427 is restored to its normal position by means of the downdrive power magnet 406, the circuit of which may be followed from battery through the winding of said magnet, upper left and upper right contacts 412 (11+12), left back contact of relay 400 to ground. If the sender selector 428 is the first to reach its normal position, or as soon after the restoration of the trunk selector 427 as said sender selector does reach its normal position, a circuit is closed from battery through the winding of sequence switch magnet 410, lower right contact 409 (3+11), normal position segment 433, brush 432, upper left contact 418 (3 $\frac{3}{4}$ +18) to ground. Sequence switch 410 thereupon moves out of position 11 and into position 12. If at this time the trunk selector switch 427 has reached normal, or as soon thereafter as said switch does reach normal, a circuit is closed from battery through the left hand winding of relay 400, contact 425 (10 $\frac{3}{4}$ +12 $\frac{3}{4}$), normal position 430, brush 429 to ground, and the relay 400 by energizing completes a circuit from ground through its outer right front contact, upper left contact 417 (12), winding of sequence switch magnet 410 to battery. Sequence switch 410 thereupon leaves position 12 and moves into its normal position.

When the sequence switch 410 leaves position 8 $\frac{1}{4}$, the lower left contact 412 opens and ground is removed from the conductor 130

447. The removal of this ground potential permits the deenergization of relay 501, and a circuit is thereby closed from ground through the left back contact of said relay, 5 upper right contact 507 (2+18), winding of the sender sequence switch magnet 510 to battery. The sender sequence switch moves from position 16, through position 18 and into its normal position, 1.

10 Considering the incoming selector switch it will be remembered that the sequence switch 110 moves from position 11 into position 12 at the initiation of the restoration of the register sender and the trunk finder 15 and sender selector switches. In position 12 of sequence switch 110, a test is made to determine if the originating operator in the manual office still has her cord circuit inserted in the jack of the trunk 100, 101. If 20 so the relay 103 will be energized in a manner similar to that explained in the above mentioned patent to Lundell and Clark No. 1,342,823, issued June 8, 1920. With relay 103 operated, a circuit is closed from ground through the contact of this relay, upper left contact 105 (12+17), lower contact 107 (8+17), right hand winding of relay 104 to battery. Relay 104 operates and closes a circuit from ground through the lower contact 30 108 (1+12 $\frac{1}{4}$), outer front contact of relay 104, lower left contact 109 (12), winding of sequence switch 110 to battery, driving said sequence switch out of position 12 and into position 15, which is the talking 35 position.

The sequence switch 210 after leaving position 6 in the manner hereinbefore described, advances to subsequent positions where a test is made of the condition of the 40 called subscriber's line in any well-known manner, and upon finding the line idle, said sequence switch finally advances to a talking position which is shown in the drawing as position 15. After the incoming selector 45 sequence switch 110 has been advanced out of position 12, ringing current may be applied to the called subscriber's line in any suitable manner. The connection has now 50 been completely established and conversation may take place over the completed talking circuit.

Release of the connection.

After conversation has been finished and 55 the connection is no longer required, the originating operator in the manual office by taking down her cord circuit permits the deenergization of relay 103, which in turn causes the deenergization of relay 104. A 60 circuit is now closed from battery through the lamp 117, upper contact 108 (3+18), outer back contact of relay 104, lower left contact 111 (13+18), interrupter 146 to ground. The interrupter 146 causes the 65 lamp 117 to flash, signifying to the op-

erator that the switches may be released. The operator thereupon depresses the key 118, closing a circuit from ground through the contacts of said key, lower right contact 116 (10+17), winding of sequence 70 switch magnet 110 to battery.

Sequence switch 110 moves into position 18 where a circuit is closed from battery through the winding of the downdrive power magnet 123, right contact 115 (18) 75 to ground. The brush shaft 145 is restored to its normal position whereafter a circuit is completed from battery through the winding of sequence switch magnet 110, upper right contact 116 (6+18), segment 135, brush 132 to ground. Sequence switch 110 moves out of position 18 and into position 1.

When the sequence switch 110 leaves position 17, it opens at its lower right contact 113 a holding circuit for relay 200. Relay 200 on deenergizing establishes a circuit from ground through its right back contact, lower contact 202 (14+17), winding of sequence switch magnet 210 to battery. Sequence switch 210 of the final selector switch 90 is driven out of position 15 and into position 18. In this position the brush shaft 231 is restored to its normal position by means of a circuit from battery through the winding of the downdrive power magnet 214, contact 206 (18), to ground. When the brush shaft 231 reaches normal, a circuit is closed from battery through the winding of sequence switch magnet 210, upper contact 202 (18), normal position segment 225, brush 222 to ground. Sequence switch 210 leaves position 18 and moves into position 1, and the circuit of the power magnet 214 is severed.

Establishment of a call involving 105 translation.

In considering the establishment of the connection just described, a called line number was chosen which did not involve a 110 tens or units digit greater than four, that is, one belonging to the second group of five. Accordingly, the register relays which control the final selector switch and its tens and units movements, determine that the 115 number of counting relays to be operated during this movement was something less than five. The next case to be discussed is one wherein the number of the called line contains tens and units digits in the second 120 group of five, or greater than four, and which will consequently involve the operation of the final switch to make selections in the second five. This means that instead of operating a variable number of counting relays less than five, it will be necessary to operate a variable number of these relays which is greater than five, and therefore greater than the possible number of settings 125 that the registers are capable of taking. To 130

make this feature possible the relay 500 is adapted to be energized whenever a registration involving a digit greater than four is produced on the register relays to cooperate with the register relays and determine that in addition to operating a variable number of counting relays corresponding to the value of such registration, an extra group of five counting relays will also be operated.

It will be noted that the relay 500, which acts as a translation relay in connection with the different registers for determining the number of counting relays to be operated, while these registers are controlling the movement of the selective switch, is the same relay which serves during the transfer of the registration from the keyboard to the sender to associate the control circuit over which the impulses are transmitted with the successive registers.

Assume, therefore, that the number of the called line communicated to the operator by the operator in the distant manual office is 6368. The operator on receiving this number depresses the No. 6 thousands key 304, the No. 3 hundreds key 305, the No. 6 tens key 306, and the No. 8 units key 308.

The first two keys 304 and 305 being the same as the ones concerned in the previous call, the incoming brush and group registers take the same settings. Following the incoming brush and group registrations, the sequence switches 310 and 510 move into positions 4, respectively, as hereinbefore explained. In position 4 of sequence switch 310, the above traced circuit for relay 339 is closed, this relay remaining deenergized due to the shunt upon its winding at the left hand normal contacts of the relay 338. Another circuit is closed from ground through the inner contact of relay 339, left hand winding of relay 338, right contact 337 (4), middle contacts of key 306, conductor 364, upper left contact 328 (4), conductor 357, thence to the conductor 446, upper left contact 516 ($3\frac{3}{4}+4$), conductor 533, left hand winding of relay 606 to battery. Relay 606 although marginal operates since only a low resistance is included in the circuit thereof and locks over its right hand winding to the grounded conductor 535. Another circuit is closed from battery through the upper left contact 366 ($3\frac{3}{4}+4$), both windings of the relay 347, upper right contact 349 (1+5), left contacts of key 306, upper left contact 327 ($3\frac{3}{4}+4$), lower left contact 326 ($1\frac{3}{4}+5$), conductor 356, thence to conductor 445, lower left contact 519 ($3\frac{3}{4}+4$), conductor 528, right hand winding of relays 605 and 603 to ground. Since the high resistance winding of relay 347 is included in this circuit, only the relay 603 operates, relay 605 being of a marginal character. Relay 603 locks in a circuit through its left

hand winding and contact through the grounded conductor 535. With relays 338 and 347 both energized, a circuit is established from battery through the upper right contact 363 (4), low resistance 335, right contact of relay 338, right contact of relay 347, conductor 355, thence to conductor 448, right hand winding of relay 615, conductor 542, lower right contact 515 (4), winding of relay 502 to battery. Only the low resistance 335 is included in the circuit traced and consequently marginal relay 615 is operated.

This relay locks through its left hand winding and left contact, conductor 539, lower left contact 506 ($1\frac{3}{4}+14$) to ground. Relay 502 also operates and advances the sequence switch 510 out of position 4 into position 5. On leaving position 4, sequence switch 510 opens the holding circuits of relays 338 and 347 and these relays become deenergized, whereafter sequence switch 310 leaves position 4 and moves into position 5 as described.

With sequence switch 310 in position 5, the previously traced circuit is closed for relay 322. Also a circuit is established from battery through the upper left contact 363 ($4\frac{3}{4}+5$), right hand low resistance winding of relay 332, left contacts of key 308, upper right contact 329 ($4\frac{3}{4}+5$), conductor 357 and thence to conductor 446, lower right contact 516 (1+5), upper right contact 517 ($4\frac{3}{4}+5$), conductor 532, right hand winding of relays 600 and 602 to ground. Only the low resistance winding of relay 332 is included in the circuit traced, and hence both the marginal relay 600 and the sensitive relay 602 become operated. These relays both lock in circuits through their left hand windings and left contacts and conductor 535 to ground. Furthermore, a circuit is closed from ground through the outer contact of relay 322, left hand winding of relay 323, right contact 333 (5), middle contacts of key 308, upper right contact 326 (5), lower left contact 326 ($1\frac{3}{4}+5$), conductor 356, thence to conductor 445, lower right contact 519 ($4\frac{3}{4}+5$), conductor 527, left hand winding of relay 601 to battery. Due to the fact that only the low resistance winding of relay 323 is included in this circuit, the marginal relay 601 becomes operated and locks through its right hand winding to the grounded conductor 535. With both relays 323 and 332 operated, a circuit is closed from ground through the lower left contact 324 (5), low resistance 325, right contact of relay 323, left contact of relay 332, upper left contact 330 (5), conductor 355, thence to conductor 448, right hand winding of relay 604, conductor 538, left contact 514 (5), right hand winding of relay 500 to battery. Only the low resistance 325 is included in the circuit traced, and hence the marginal relay 604 operates

in series with relay 500. Relay 604 locks through its left hand winding to the grounded conductor 539. Relay 500 operates to advance the sender sequence switch 5 out of position 5 and into position 6 in the manner hereinbefore described. The sender sequence switch 510 leaving position 5, opens the circuits of relays 323 and 332, and these relays become deenergized and the sequence 10 switch 310 thereafter moves into position 6. Following this, the operator's keyboard is released and the sequence switch 410 is advanced into position 8.

The incoming selector switch 125 is operated in its group selecting movement and in its trunk movement in precisely the same manner as already explained following which the sequence switch 110 goes into position 11 for selection beyond.

20 Thereafter, the brush selecting operation of the final switch takes place, sequence switch 210 moves into position 3 and the sender sequence switch 510 advances into position 12. When sequence switch 510 moves 25 into position 12, a circuit is closed from battery through both windings of relay 500 in series, lower right contact 509 (11+12), conductor 559, right contact of relay 615 to ground. With sequence switch 210 in position 30 3 and sequence switch 510 in position 12, the fundamental circuit is closed for controlling the tens selective movement in the final switch 215. Relay 201 operates, which causes the advance of sequence switch 210 35 into position 4 and locks in a circuit through its right contact, previously traced. With sequence switch 210 in position 4, the up-drive magnet 213 is energized and the brush shaft commences its upward movement to 40 select the proper group of ten terminals.

The stepping relay 520, also energizing in the fundamental circuit, completes a circuit from ground through the lower left contact 513 (8+12), conductor 546, contact 45 of relay 520, conductor 545, upper left contact 512 (12), upper left contact 511 (12), conductor 556, right front contact of relay 603, left front contact of relay 606, outer right back contact of relay 605, conductor 50 621, thence to conductor 526, Fig. 5, back contact of counting relay 523, winding of counting relay 524 to battery. Relay 524 operates and closes a locking circuit for itself and relay 523, but the latter relay can- 55 not operate due to the shunt circuit closed by the stepping relay 520.

The brush shaft 231 in moving upwardly in the group selecting movement, advances the commutator brush 224 into connection 60 with the first metallic segment of commutator 227, causing the circuit hereinbefore traced to be closed for relay 201. The closure of this circuit shunts the stepping relay 520, which becomes deenergized and 65 opens the shunt around the winding of

counting relay 523. Relay 523 operates and locks in series with relay 524 to ground over the upper left contact 506 (12). When the brush 224 disengages the metallic segment, the shunt is removed and stepping relay 520 again operates, closing the stepping circuit now by way of conductor 526, front contact of relay 523, conductor 560, left contact of relay 500, back contact of the No. 9' counting relay 561, winding of the No. 9 counting relay 562 to battery. The relay 562 operates and closes a locking circuit for itself in series with the winding of relay 561, the latter relay, however, remaining deenergized at this time. When the brush 224 engages the next metallic segment, and relay 520 becomes deenergized, the shunt is removed and the counting relay 561 operates and locks in series with relay 562. In response to the next operation of the stepping relay 520, the stepping circuit is extended by way of the front contact of relay 561, back contact of the No. 8' counting relay 563, winding of the No. 8 counting relay 564 to battery. Relay 564 operates and prepares a locking circuit for itself and relay 563. This procedure continues, an additional pair of counting relays being energized and locked for each group of ten terminals passed over by the selected set of brushes until finally the No. 5' and No. 5 relays 565 and 566 are operated. Upon the next energization of the stepping relay 520, the stepping circuit is completed from ground through the lower left contact 513 (8+12), conductor 546, contact of relay 520, conductor 545, upper left contact 512 (12), upper left contact 511 (12), conductor 556, thence as traced to the conductor 621 and from there to conductor 526, Fig. 5, front contact of relay 523, conductor 560, left contact of relay 500, through the front contacts of all prime relays from relay 561 to relay 565, conductor 567, lower left contact 517 (6+18), lower left contact 516 (6+18), right front contact of relay 500, upper left contact 503 (6+18), winding of the zero counting relay 522 to battery. Relay 522 operates and closes a series circuit for itself and the 0' counting relay 521. When, following the extension of the stepping circuit through the winding of the zero relay 522, the brush 224 next engages a metallic segment of the commutator 227, the stepping relay 520 becomes deenergized and removes the shunt from around the winding of the 0' counting relay 521. Relay 521 operates and opens the fundamental circuit, and also closes the circuit for driving sequence switch 510 out of position 12 and into position 14. As soon following the opening of the fundamental circuit at the sender as brush 224 engages an insulating segment of commutator 227, relay 201 becomes deenergized, opens the circuit of the power magnet 213 120

and closes a circuit for driving sequence switch 210 out of position 4 and into position 5.

The fundamental circuit is again closed for the units selecting movement of the switch, and relays 201 and 520 become energized. Relay 201 closes a circuit for driving the sequence switch 210 into position 6 where the circuit of the updrive power magnet 213 is established for moving the brush shaft 231 to carry the brushes over the sets of terminals. Relay 520 on energizing in series with relay 201 closes a circuit from ground through the lower right contact 513 (14), conductor 545, contact of relay 520, conductor 546, lower left and upper right contacts 511 (14), conductor 538, right front contact of relay 602, left front contact of relay 601, outer right front contact of relay 600, conductor 622, thence to conductor 555 of Fig. 5, back contact of counting relay 548, winding of counting relay 568 to battery. Relay 568 operates and closes a holding circuit for itself in series with the winding of the relay 548.

As the brush shaft 231 moves over the terminals in the selected group of ten, commutator brush 222 makes engagement with the successive metallic segments of the terminal selecting commutator 228. At each contact of the brush 222 with the commutator 228, a circuit is closed for holding the relay 201 energized and for shunting down the stepping relay 520 in the fundamental circuit. For each energization and deenergization of the stepping relay 520, an additional pair of counting relays are operated and locked until finally the No. 1 and No. 1' counting relays 524 and 523 are operated.

It will be observed that when sequence switch 510 moves into position 14 preparatory to the units selecting movement, a circuit is closed from battery through the windings of relay 500, left contact 509 (13+14), conductor 541, right contact of relay 604 to ground. The energization of relay 500 indicates that the registration on the units register is representative of a digit greater than four, and therefore calls for the operation of the additional group of five pairs of counting relays to properly position the selector switch.

When the counting relay 523 is operated during the units selecting movement, the stepping circuit is extended as previously traced by way of conductor 555, front contact of relays 548, 549 and 523 in series, conductor 560, left contact of relay 500, back contact of the counting relay 561, winding of counting relay 562 to battery. Relay 562 operates and prepares a holding circuit for itself and relay 561. The brush shaft 231 continues its upward movement

and the counting relays are operated in pairs until the No. 5 and the No. 5' counting relays 566 and 565 are operated, at which time the stepping circuit is then extended by way of conductor 567 lower left contact 517 (6+18), lower left contact 516 (6+18), right front contact of relay 500, upper left contact 503 (6+18), winding of the zero counting relay 522 to battery. Relay 522 operates and closes a circuit for relay 521, which thus operates as soon as the brushes have accurately centered at the desired set of terminals and the commutator brush 222 encounters an insulating segment of the commutator 228. Relay 521 on operating opens the fundamental circuit and closes the circuit as described for driving the sequence switch 510 into position 16.

From this point on the restoration of the sender and the preparation of the incoming and final switches for completing the conversational circuit and the release of all other apparatus, takes place in precisely the same manner as hereinbefore described in connection with a previous call.

Briefly stated, the register controlling mechanism consists of a plurality of registers which receive registrations characterizing the digits of wanted subscribers' numbers. These registers are positioned by means of impulses transmitted over a control circuit from the operator's keyboard, which control circuit is associated first with one register and then with another in succession after receiving the registration. The switches are set in motion and operate through a distance determined by the value of the registration recorded on the registers, this being accomplished by the counting relays which operate in numbers determined directly by the setting of the registers.

Owing to the limited number of settings that the registers are capable of taking as compared with the number of selections that the switches must perform, translation as regards the division of digits into two groups of five is necessary. In other words, all digits from 0 to 4, in the first group of five, may be set up on the register and will determine the operation of a corresponding number of counting relays. However, if a digit, greater than four, in the second group of five is concerned, then the register will take a certain setting, the same as it would if the digit were in the first group of five, but in addition the translation relay 500 is operated. The function of the relay 500 when operated in conjunction with the registration set up on one of the registers is to determine that the register exercise a control over the selective movement of the switch different from what it would were the digit involved one that belonged in the first group of five. What the relay 500

does, as has been seen, is to render effective the last group of five counting relays, thereby virtually adding to the number of impulses transmitted over the fundamental 5 five impulses in addition to those normally determined by the setting of the register. Relay 500, as was pointed out in detail, in addition to its function of varying the control that a register has over the extent of 10 movement of the selective switch, dependent upon the nature of the digit, also acts to bring about the association of the impulse control circuit leading from the keyboard, with the registers of the sender during the 15 time that the record is being transferred from the keys to said registers.

What is claimed is:

1. In a telephone exchange system, the combination of a selective switch for extending connections, a register controlling mechanism, a controlling circuit for variably setting said register mechanism, a device for causing the association of said controlling circuit with the register mechanism, means controlled by said register mechanism for operating the selective switch an amount corresponding to the setting of the register mechanism, and means controlled by said device for modifying the control of the register mechanism over said switch operating means to cause the operation of said switch through an amount other than that corresponding to the setting of said register mechanism.
2. In a telephone exchange system, the combination of a selective switch for extending connections, a register controlling mechanism, a controlling circuit for variably setting said register mechanism, a device for causing the association of said controlling circuit with the register mechanism for operating the selective switch an amount corresponding to the setting of the register mechanism, and means controlled by said device for modifying the control of the register mechanism over said switch operating means to cause the operation of said switch through an amount greater than that corresponding to the setting of said register mechanism.
3. In a telephone exchange system, the combination of a selective switch for extending connections, a register controlling mechanism, a controlling circuit for variably setting said register mechanism, a device for causing the association of said controlling circuit with the register mechanism, means controlled by said register mechanism for operating the selective switch to an extent corresponding to the setting of the register mechanism, and means controlled by said device for modifying the control of the register mechanism over said switch operating means to cause

the operation of said switch to an extent 65 greater by a definite amount than that corresponding to the setting of said register mechanism.

4. In a telephone exchange system, the combination of a selective switch for extending connections, a register controlling mechanism, a controlling circuit for variably setting said register mechanism, a device actuated over said controlling circuit for causing the successive association of said 75 controlling circuit with the register mechanism, means controlled by said register mechanism for operating the selective switch an amount corresponding to the setting of the register mechanism, and means 80 controlled by said device for varying the control of the register mechanism over said switch operating means to cause the operation of said switch through an amount other than that corresponding to the setting of 85 said register mechanism.

5. In a telephone exchange system, the combination of a selective switch for extending connections, a register controlling mechanism, a controlling circuit, means for sending impulses over said circuit to variably set the register mechanism, a device for causing the successive association of said controlling circuit with the register mechanism, means controlled by said register mechanism for operating the selective switch an amount corresponding to the setting of the register mechanism, and means controlled by said device for modifying the control of the register mechanism over said switch operating means to cause the operation of said switch through an amount other than that corresponding to the setting of 95 said register mechanism.

6. In a telephone exchange system, the combination of a selective switch for extending connections, a register controlling mechanism, a controlling circuit, means for sending a plurality of codes of impulses over the controlling circuit for setting said 100 register mechanism in accordance with desired designations, a device for causing the association of the controlling circuit with said register mechanism, means controlled by said register mechanism for operating the selective switch an amount corresponding to the setting of the register mechanism, and means controlled by said device for varying the control of the register mechanism over said switch operating means to cause the operation of said switch through an amount other than that corresponding to the setting of 105 said register mechanism.

7. In a telephone exchange system, the combination of a selective switch for extending connections, a register controlling mechanism comprising a plurality of registers, a controlling circuit for variably setting 120

5 said registers, a device for causing the association of said controlling circuit with said registers, means controlled by said registers for operating the selective switch
 10 5 an amount corresponding to the setting of said registers, and means controlled by said device for modifying the control of the registers over said switch operating means to cause the operation of said switch through
 15 10 an amount different from that corresponding to the setting of said registers.

8. In a telephone exchange system, the combination of a selective switch for extending connections, a register controlling mechanism comprising a plurality of registers, a controlling circuit, a device for causing the association of said controlling circuit with said registers in succession, means for sending impulses over the controlling 20 circuit to set said registers, means controlled by said registers for operating the selective switch an amount corresponding to the setting of such registers, and means controlled by said device for modifying the 25 control of the registers to cause the operation of said switch through an amount other than that corresponding to the setting of said registers.

9. In a telephone exchange system, the combination of a selective switch for extending connections, a register controlling mechanism comprising a plurality of registers each consisting of a plurality of relays, a controlling circuit for variably setting 30 said relay registers, a device for causing the association of said controlling circuit with said registers in succession, means controlled by said registers for operating the selective switch an amount corresponding 35 to the setting of said registers, and means controlled by said device for modifying the control of said registers over said switch operating means to cause the operation of said switch through an amount other than 40 that corresponding to the setting of said registers.

10. In a telephone exchange system, the combination of an operator's position, a selective switch for extending connections, 45 a register controlling mechanism comprising a plurality of registers, a controlling circuit, means actuated by the operator for sending impulses over said controlling circuit to variably set said registers, a device for successively associating said controlling circuit with said registers, means controlled by said registers for operating the selective switch an amount corresponding to the setting of such registers, and means controlled by said device for altering the control of said registers to cause the operation of said switch through an amount other than that corresponding to the setting of said registers.

65 11. In a telephone exchange system, the

combination of an operator's position, a keyboard thereat, a selective switch for extending connections, a register mechanism, a controlling circuit, means controlled over said circuit by said keyboard for variably 70 setting said register mechanism, a device for causing the association of said controlling circuit with the register mechanism, means controlled by said register mechanism for operating the selective switch an amount 75 corresponding to the setting of the register mechanism, means controlled by said device for modifying the control of the register mechanism over said switching operating means to cause the operation of said switch through an amount other than that corresponding to the setting of said register mechanism.

12. In a telephone exchange system, the combination of a selective switch for extending connections, a register controlling mechanism, a controlling circuit for variably setting said register mechanism, a relay for causing the association of said controlling circuit with the register mechanism, means controlled by said register mechanism for operating the selective switch an amount corresponding to the setting of the register mechanism, and means controlled by said relay for modifying the control 85 of the register mechanism over said switch operating means to cause the operation of said switch through an amount other than that corresponding to the setting of said register mechanism. 90

13. In a telephone exchange system, the combination of a selective switch for extending connections, a register controlling mechanism, a controlling circuit for variably setting said register mechanism, a relay actuated over said controlling circuit for causing the successive association of said circuit with the register mechanism, means controlled by said register mechanism for operating the selective switch an amount 100 corresponding to the setting of the register mechanism, and means controlled by said relay for varying the control of the register mechanism over said switch operating means to cause the operation of said switch through an amount other than that corresponding to the setting of said register mechanism. 105

14. In a telephone exchange system, the combination of a selective switch for extending connections, a register controlling mechanism comprising a plurality of registers, a controlling circuit, a relay for causing the association of said controlling circuit with said registers in succession, means for variably setting said registers over the controlling circuit, means controlled by said registers for operating the selective switch an amount corresponding to the setting of such registers, and means controlled by said relay for altering the control of said registers. 115 120 125 130

ters to cause the operation of said switch through an amount differing from the amount corresponding to the setting of said registers.

- 5 15. In a telephone exchange system, the combination of a selective switch for extending connections, a register controlling mechanism, a controlling circuit for variably setting said register mechanism, a device for causing the association of said controlling circuit with the register mechanism, a plurality of counting relays, means controlled by said register mechanism for operating a definite number of said counting relays to determine the operation of said selective switch to an extent corresponding to the setting of said register mechanism, and means controlled by said device for modifying the number of counting relays operated under the control of said register mechanism to operate said selective switch to an extent different from that corresponding to the setting of said register mechanism.
- 10 16. In a telephone exchange system, the combination of a selective switch for extending connections, a register controlling mechanism comprising a plurality of registers, a controlling circuit for variably setting said register mechanism, a relay for causing the association of said controlling circuit successively with the registers of said mechanism, a plurality of counting relays, means for operating a number of said counting relays equivalent to the setting of
- 15 20 25 30 35

said register mechanism to determine the operation of said selective switch to an extent corresponding to the setting of said register mechanism, and means controlled by said relays for causing the operation of a definite number of counting relays in addition to the number of counting relays operated in correspondence with the setting of said register mechanism to determine the operation of said selective switch to an extent greater than that corresponding to the setting of said register mechanism.

17. In a telephone exchange system, the combination of a plurality of automatic selective switches for extending connections, a register controlling mechanism, comprising a plurality of registers, a controlling circuit for variably setting said register mechanism, a relay for causing the association of said controlling circuit successively with the registers of said mechanism, means controlled by said register mechanism for operating said selective switches an amount corresponding to the setting of said register mechanism, and means controlled by said relay for modifying the control of the register mechanism over one of said selective switches to cause the operation of such switch through an amount other than that corresponding to the setting of said register mechanism.

In witness whereof, I hereunto subscribe my name this 24th day of December A. D. 1921.

FRANKLIN ANDREW STEARN.
